UNITED STATES PATENT OFFICE

DUDLEY H. SCOTT AND HOWARD D. STONEBACK, OF CLEVELAND, OHIO, ASSIGNEES TO
THE HUMPHREY COMPANY, OF CLEVELAND, OHIO, A CORPORATION OF OHIO

AMUSEMENT DEVICE

Application filed June 18, 1931. Serial No. 544,766.

This invention relates to amusement devices of the type known as "dark rides" wherein a passenger car is propelled along a trackway within an enclosure whereby the way is maintained in such darkness that the passengers' senses of space, direction, location, etc., become confused. In such an amusement device the track is arranged to provide a devious way for the car, leading from without the enclosure through a light trap produced by baffles or double doors, with many convolutions within the enclosure, and out through another light trap. Various effect apparatus is arranged along the way within the enclosure, such as thunder, air blast and scenic machines, and where lighting is employed as in the latter, baffles are so arranged that the light is invisible from parts of the trackway other than those immediately adjacent.

This invention relates more particularly to one of such effects, intended to give the passenger the illusion of moving, as revolving, in infinite space; and, briefly comprises a member located in such relation to a portion of the trackway that a car on the latter will move generally toward the member and its direction of movement, the member having luminescent configurations arranged to be visible to an occupant of the car on said track portion.

The luminescence is essential that the effect of distance may be had, as it has been found that should other means of illumination be employed, light rays would be emitted which would so illuminate other adjacent objects such as portions of the car and trackway as to make apparent the true relation of the parts; and it is an object of our invention to employ luminescent material for the purpose described.

Luminescent material, however, maintains its luminescence only a very short time after each exposure to light, so that in the described arrangement light means must be

provided to which the configurations may be periodically exposed to receive energization; and this is a further object of the invention.

It will be apparent that unfortunately the effect of luminescence is entirely destroyed if its energizing light means be functioning while the configurations are visible to the passenger. We therefore, as another object of our invention provide means controlled by the movement of the car for interrupting the functioning of the light means when the car is on a portion of the trackway from which the configurations are visible to the occupant.

The exact nature of this invention together with further objects and advantages thereof will be apparent from the following description taken in connection with the accompanying drawings, in which Figs. 1 and 2 are sectional and side elevations respectively, illustrative of an embodiment of the invention wherein the configuration-bearing member is cylindrical, parts being broken away to show details of construction; Fig. 3 is a diagrammatic showing of the light control means employed, the figure also illustrating the plan arrangement of parts appearing in Figs. 1 and 2; Figs. 4 and 5 are elevation and plan views respectively of another embodiment of the invention wherein the configurations are borné upon a disk, Fig. 4 being taken as upon line 4-4, Fig. 5; Figs. 6 and 7 show another embodiment, wherein the configurations are carried upon a ring, Fig. 6 being a front elevation similar to Fig. 4 and Fig. 7, being a section as indicated line 7-7, Fig. 6.

With reference now to the drawings and particularly Figs. 1-3 thereof, 1 indicates a pair of rails which provide a trackway along the floor 2 of a building enclosure whose interior is maintained dark as indicated by the walls and ceiling 3; the purpose of the trackway being to guide a car 4 therealong. The rails 1 may have connection with one side

of a line from a source of electric power, and a rail 1' may be provided alongside the track to supply the return connection, so that the car 4 may be equipped with a driving motor

5 M receiving energy from the rails through collectors 5 for propulsion along the trackway.

A cylindrical member 6 is mounted as upon rollers 7 to be driven about its axis by a motor 10 acting through a belt 9. The cylinder 6 is located as indicated Figs. 1 and 2 to extend beneath the floor 2 with its axis along and above a stretch 10 of the trackway which leads through the cylinder on a floor bridge portion 11; and the cylinder is of sufficient diameter that car and passengers may pass along the trackway stretch therethrough with ample clearance therefrom.

The inner surface of the cylinder 6 is provided with configurations here shown as in the form of stars 12 spaced, as indicated in Fig. 2, along helical lines. The configurations may be simply painted on the surface with luminescent paint, the remainder of the 25 surface preferably having a dead black or other effective light-absorbing surfacing serving as an invisible background.

That the luminosity of the configurations may be maintained I provide light means for 30 energizing the luminescent material thereof, comprising electric lamps 13 arranged to direct their illumination upon a portion of the surface of the cylinder; and that the light emitted by the lamps 13 may be confined so 35 far as possible I locate the lamps beneath the floor bridge portion 11 as indicated in Figs. 1 and 2. With reference now to the circuit diagram portion of Fig. 3, as there shown the lamps 13 may be arranged in a circuit connected with the rails 1 and 1' for current supply. That the functioning of the light 40 may be interrupted when the car 4 is on that portion of the trackway from which rays escaping from the lamps 13 might destroy the effect of the luminosity of the configurations, I provide switch means 14 in the lamp circuit. The switch 14 may be simply a relay switch, normally closed to maintain the lamps energized, and having a coil 15 upon 45 energization of which the lamp circuit will be broken. The circuit of the coil 15 includes a connection 16 with the L1 rail and a third rail 17 extending alongside the track so far as it is desired that the lights 13 remain out.

50 A collector 18 is mounted on the car 4 to cooperate with the rail 17, the contactor 18 having connection with the L2 rail as at 19 through one of the contactors 5.

It will be apparent that by this circuit control arrangement the lights 13 will be on to 60 energize the configurations 12 except while the car 4 is on the trackway portion determined by the location and extent of the third rail 17. It is preferable that the trackway have a bend as at 20 immediately ahead of

the cylinder 6, with the rail 17 extending around this bend, and that the trackway include a similar bend shortly beyond the cylinder; so that escaping rays from the lamps 13 will be effectively trapped from other locations along the trackway.

With reference now to the modification illustrated Figs. 4 and 5, a less expensive construction is shown wherein a disk 6a is arranged to be rotated on its axis by a motor 8a, and a stretch 10a of the track is arranged to lead the car toward the disk along its axis, with a sharp bend indicated in Fig. 5 just before the disk; so that the disk will be directly ahead of the car while the latter is on the stretch 10a. The configurations here shown are in the form of a spiral lines 12a. A lamp 13a is arranged to illuminate the face of the disk subject to interruption governed by the third rail 17a as before.

The form shown in Figs. 6 and 7 is a modification wherein a ring 6b is employed; the ring extending through slots in the floor and mounted to be rotated on its axis by motor 8b, with the track 1 running through the opening in the ring. Here the configurations are in the form of circles 12b upon the face of the ring toward a stretch of trackway as in the case of the disk 6a. Lights 13b are disposed beneath the floor to illuminate this face of the ring and are controlled by the position of the car on the track, to go off as the car approaches the ring, by a circuit arrangement such as that already described.

What we claim is:

1. In an amusement device of the class described, a member having luminescent configurations, a car, a trackway therefor having a portion arranged to direct the car occupants' vision toward said configurations, light means for energizing said configurations, and means for interrupting the functioning of said light means when said car is on said trackway portion.

2. In an amusement device of the class described, a moving member having luminescent configurations, a car, a trackway therefor having a portion arranged to direct the car occupants' vision toward said configurations, light means for energizing said configurations, and means for interrupting the functioning of said light means when said car is on said trackway portion.

3. In an amusement device of the class described, a car, a trackway therefor, a member having luminescent configurations arranged to be visible to an occupant of said car on a portion of said trackway, said member being arranged for movement to move said configurations transversely of said trackway portion, light means for energizing said configurations, and means controlled by the movement of said car for interrupting the functioning of said light means when said car is on said trackway portion.

4. In an amusement device of the class described, a rotating member, a car, a trackway therefor having a portion adjacent said member, said member having luminescent configurations arranged to be visible to an occupant of said car on said portion, light means for energizing said configurations, and means controlled by the movement of said car for interrupting the functioning of said light means when said car is on a portion of said trackway from which said configurations are visible to said occupant. 5. In an amusement device of the class described, a rotating member, a car, a trackway therefor having a stretch adjacent said member adapted to direct said car generally along the axis thereof, said member having a surface portion of large area arranged to be visible to an occupant of said car on said stretch, said surface portion having configurations disposed in a pattern concentric with said axis. 6. In an amusement device of the class described, a member having a through opening and arranged for rotation about said opening, a car, a trackway therefor having a stretch leading through said opening, said member having luminescent configurations arranged to be visible to an occupant of a car on said stretch, light means for energizing said configurations, and means controlled by the movement of said car for interrupting the functioning of said light means when said car is on said stretch. 7. In an amusement device of the class described, a member having a through opening and arranged for rotation about said opening, a car, a trackway therefor having a stretch leading through said opening, said member having luminescent configurations arranged to be visible to an occupant of a car on said stretch, light means arranged below said trackway for energizing said configurations, and means controlled by the movement of said car for interrupting the functioning of said light means when the car is on said stretch. 8. In an amusement device of the class described, a rotating cylinder, a car, a trackway therefor having a stretch leading through said cylinder, said cylinder having luminescent configurations, and means controlled by the movement of said car for interrupting the functioning of said light means when said car is on said stretch. 9. In an amusement device of the class described, a rotating cylinder, a car, a trackway therefor having a stretch leading through said cylinder, said cylinder having luminescent configurations on its inner surface, light means arranged below said trackway for energizing said configurations, and means controlled by the movement of said car for interrupting the functioning of said light means when said car is on said stretch.
10. In an amusement device of the class described, a rotating member, a car, a trackway therefor having a stretch adjacent said member adapted to direct said car generally along the axis thereof, said member having a surface portion of large area arranged to be visible to an occupant of said car on said stretch, said surface portion having configurations disposed in a pattern concentric with said axis.
